AIR CLEANER

Ralph R. Layte, Short Hills, N. J., assignor to
Motor Improvements, Inc., Newark, N. J., a cor-
poration of Delaware

Application October 3, 1930, Serial No. 486,139

12 Claims. (Cl. 183—75)

This invention relates to air cleaners and has for an object a simple, inexpensive and efficient device for separating water, oil, dirt and other foreign matter from a stream of air.

A device embodying the invention comprises a helix formed from a flat metal ribbon of minute thickness and which is relatively wide in comparison to its thickness, the ribbon being preformed so that it naturally lies in helical form with its flat faces normal to the axis of the helix, the adjacent turns being slightly spaced to form minute aperture. The helix is so supported as to provide a plurality of downwardly extending ducts for conducting air after its passage through the helix downwardly and discharging the air into a chamber having an outlet from its upper portion and a drainage opening in its lower portion. The unit above described is contained within a casing to which air to be cleaned is supplied. Water in liquid form is trapped in the space between the unit and the casing and oil is retained on the outer surface of the helix, probably due to adhesion, while the moisture laden air passes through the interstices between the turns of the helix, and owing to the very thin stream into which the air is separated and to the large metal surface that is exposed to the air, moisture coagulates between the turns into droplets which are of sufficient size to fall of their own weight, thus freeing the air from its moisture. Inasmuch as the space between the ribbons is constantly partially filled with water, dirt particles are washed out of the air by the water and fall with the droplets. This device effects condensation of water vapor between the turns and the liquefied water is separated from the air by gravity. This device is highly efficient and separates from the air substantially all the moisture contained therein.

Other objects, novel features and advantages of this invention will be apparent from the following specification and accompanying drawing, wherein:

Fig. 1 is a vertical section through an air cleaner embodying the invention;

Fig. 2 is a section on the line 2—2 of Fig. 1, and

Fig. 3 is a fragmentary enlarged perspective view.

A head 10 is provided with a screw threaded central recess in which is arranged a threaded bushing 11. A substantially cylindrical drum 12 is supported by the bushing 11 and is provided with vertical peripheral flutes 13. A cylinder 14 surrounds and is supported by the drum

12 and forms with the flutes conduits closed at their upper ends and open at their lower ends. The cylinder 14 comprises a helix formed from a metal ribbon preformed so that its turns lie with their flat faces normal to the axis of the helix and without tendency to buckle or deviate from this position. The ribbon is provided with ribs 15 which space apart the adjacent turns to form interstices. The ribbon is of minute thickness and is of relatively large width in comparison with its thickness. Preferably, the ribbon is less than .010 inch in thickness and is approximately .050 inch or more in width, the ribs being .001 to .003 inch in height, thus forming interstices of minute height. Preferably the ribbon is made of somewhat tapering cross-section in the direction radial of the cylinder with the outer edge of greater thickness than the inner edge. This results in the apertures being more narrow at the entry point of the air, thereby preventing wedging or clogging of impurities between the turns of the helix. The height of the transfer ribs 15 increases necessarily so that its top contacts with the opposed face of the adjacent turns throughout the full width thereof. The apertures thus are divergently tapered in the direction of air flow.

The bottom of the drum 12 is apertured and a cap 16 is attached thereto by screws 17. This cap extends over the side wall of the drum a short distance and engages the bottom end of the helix 14. The cap also is provided with an apertured flange 18 and with a central drainage opening. A cup-shaped member 19 receives the cap 16 within its upper end and is provided with a neck 20 closed by a plug 21 in which is threaded a drainage valve 22. The neck is connected to the lower end of a casing 23, the upper end of which fits in a recess in the head 10, the wall of the casing contacting with the periphery of the flange 18. A valve 24 is provided for draining the casing 23.

The head 10 is provided with an inlet passageway 25 which communicates with the space between the helix 14 and the wall of the casing 23. It is also provided with an outlet passageway 26 which communicates with the interior of the drum 12. The total area of the interstices in the helix exceeds considerably the area of either the inlet or the outlet passageways so that air passes through the interstices at a much lower velocity than through the inlet and outlet passageways.

Air to be cleaned is supplied to the inlet passageway 25, is passed through the narrow interstices in the helix 14, follows the ducts formed

by the flutes 13 into the passageway formed between the bottom of the drum 12 and the cap 16, after which it passes upwardly through the bushing 11 into the outlet passageway 26. Any water present in the air in liquid form is for the most part trapped in the space between the casing and cylinder and drains through the apertures in the flange 18 into the bottom of the casing. Oil present in the air is retained on the outer surface of the cylinder 14 probably by adhesion. Water vapor passes into the interstices between the turns where it is condensed due to the very thin streams into which the air is separated and to the relatively large metal surfaces to which it is exposed and also the relatively slow velocity with which it passes through the interstices. The condensate forms into droplets which are of sufficient weight to fall downwardly through the conduits formed by the flutes 13 and out through the drainage opening in the cap 16. The cleaned air passes upwardly through the drum and is discharged from the cleaner. Minute dust particles in the air are washed out by the water collected in the interstices between adjacent turns and are retained by the water and fall into the cup 19 with the water. The water collecting in the bottom of the casing 23 is dirty and oily, while that in the cup 19, except for a small amount of dust, is clean and sparkling. Most of the water collected in the casing 23 is carried into the cleaner in liquid form, while the water in the cup 19 is carried in vapor form and is condensed in the interstices of the cylinder 14.

It is to be understood of course that various modifications may be made in the structure above described, without in any way departing from the spirit of the invention as defined in the appended claims.

I claim:

1. An air cleaner comprising a fluted drum, a cylinder surrounding said drum and forming with said flutes conduits leading into the interior of said drum, said cylinder comprising a helix of thin metal ribbon having its turns minutely spaced, an outlet from the top of said drum, and a drainage opening in the bottom of said drum.

2. An air cleaner comprising a fluted drum, a cylinder surrounding said drum and forming with said flutes conduits leading into the interior of said drum, said cylinder comprising a helix of thin metal ribbon having its turns minutely spaced, an outlet from the top of said drum, a drainage opening in the bottom of said drum, a casing surrounding said drum and cylinder, and an inlet communicating with the space between said cylinder and casing.

3. In an air cleaner, a fluted drum having an outlet at the top thereof, a cylinder surrounding said drum and forming with said flutes conduits having their lower ends open, said cylinder comprising a helix of thin metal ribbon having its turns minutely spaced, a passageway communicating with said drum and the lower ends of said conduits, and a drainage outlet for said passageway.

4. In an air cleaner, a fluted drum having an outlet at the top thereof, a cylinder surrounding said drum and forming with said flutes conduits having their lower ends open, said cylinder comprising a helix of thin metal ribbon having its turns minutely spaced, a passageway communicating with said drum and the lower ends of said conduits, a drainage outlet for said passageway, a casing within which said drum and cylinder are

contained, and an inlet communicating with the space between said casing and cylinder.

5. In an air cleaner, a fluted drum having an inlet in its bottom end, a flat wire helix surrounding said drum and forming with said flutes conduits having their lower ends open, said helix having its turns minutely spaced, an apertured cap attached to the bottom end of said drum and forming with said bottom end a passageway into which said conduits discharge, and an outlet at the upper end of said drum.

6. In an air cleaner, a fluted drum having an inlet in its bottom end, a flat wire helix surrounding said drum and forming with said flutes conduits having their lower ends open, said helix having its turns minutely spaced, an apertured cap attached to the bottom end of said drum and forming with said bottom end a passageway into which said conduits discharge, an outlet at the upper end of said drum, a casing surrounding said drum and cylinder and an inlet communicating with the space between said cylinder and casing.

7. In an air cleaner, a fluted drum having an inlet in its bottom end, a cylinder surrounding said drum and forming therewith conduits having their bottom ends open, said cylinder being provided with minute apertures, an apertured cap attached to the bottom end of the drum and forming therewith a passageway into which said conduits discharge and an outlet leading from the upper end of said drum.

8. In an air cleaner, a fluted drum having an inlet in its bottom end, a cylinder surrounding said drum and forming therewith conduits having their bottom ends open, said cylinder being provided with minute apertures, an apertured cap attached to the bottom end of the drum and forming therewith a passageway into which said conduits discharge, an outlet leading from the upper end of said drum, a casing surrounding said drum and cylinder, and an inlet communicating with the space between said casing and cylinder.

9. In combination, a casing, a fluted drum within said casing, an inlet communicating with the space between said casing and drum, outlet and inlet passages in the top and bottom of said drum, a cylinder surrounding said drum and forming therewith conduits having their lower ends open, said cylinder being provided with minute apertures, an apertured cap attached to the bottom end of the drum and forming therewith a passageway providing communication between the ends of said conduits and the interior of said drum.

10. In combination, a casing, a fluted drum within said casing, an inlet communicating with the space between said casing and drum, outlet and inlet passages in the top and bottom of said drum, a cylinder surrounding said drum and forming therewith conduits having their lower ends open, said cylinder being provided with minute apertures, an apertured cap attached to the bottom end of the drum and forming therewith a passageway providing communication between the ends of said conduits and the interior of said drum, and a cup within the upper end of which said cap is received.

11. In combination, a casing, a fluted drum within said casing, an inlet communicating with the space between said casing and drum, a cylinder surrounding said drum and forming therewith conduits having their lower ends open, said cylinder being provided with minute apertures, a cap fitting over the bottom end of the drum and into which said conduits discharge, a passageway

between said cap and the interior of the drum, an outlet leading from the top of said drum, a cup within the upper end of which said cap is received, an outlet from said cap discharging into said cup, and a perforated annular member interposed between said casing and said cylinder.

12. An air cleaner comprising a fluted drum having inlet and outlet passages in its bottom and top walls respectively, a cylinder surround-

ing said drum and forming with said flutes conduits having their lower ends open, said cylinder comprising a helix of thin metal ribbon having its turns minutely spaced, a cap attached to the bottom of said drum and forming a chamber into which said conduits discharge and a drainage outlet for said chamber.

RALPH R. LAYTE.
